UNITED STATES PATENT OFFICE.

HENRY BEACH CARRE, OF NASHVILLE, TENNESSEE.

BOOKCASE.

1,277,544.

Specification of Letters Patent. Patented Sept. 3, 1918.

Application filed December 17, 1917. Serial No. 207,549.

To all whom it may concern:

Be it known that I, HENRY BEACH CARRE, a citizen of the United States, residing at Nashville, in the county of Davidson and 5 State of Tennessee, have invented a new and useful Bookcase, of which the following is a specification.

By way of explanation, it may be stated that, as is a matter of common knowledge, 10 the books on the shelves of a library frequently become misplaced, notwithstanding the expenditure of considerable care in replacing them. Further, the books upon a shelf tend to tilt laterally, thereby straining 15 and breaking the bindings, and entailing considerable expense in connection with the upkeep of a library. In view of the foregoing, the invention aims to provide means whereby the place of a book on a shelf will 20 be clearly indicated, and whereby expenses incident to the repair of broken bindings will be reduced.

Another object of the invention is to provide a novel form of place-marker and book-support, equipped with novel means for holding it in an upright position.

The invention aims to provide novel means whereby when a plurality of book-supports are used, a minimum amount of 30 space will be taken up by the book-supports, longitudinally of the shelf.

It is within the province of the disclosure to improve generally and to enhance the utility of, devices of that type to which the 35 present invention appertains. But one form of the invention is shown, and changes such as might be made by a mechanic, may be resorted to, within the scope of what is claimed, without departing from the spirit 40 of the invention.

In the drawings:

Figure 1 shows the invention in front elevation, parts being broken away;

Fig. 2 is a transverse vertical section;

45 Fig. 3 is a perspective disclosing one of the combined place-markers or book-supports;

Fig. 4 is a perspective showing one of the supports for the ends of the rod which 50 carries the place-markers; and

Fig. 5 is a section taken approximately on the line 5—5 of Fig. 1.

In the drawings, there is shown a portion 55 of a book case comprising stiles 1 and a shelf 2. Sockets 3 are provided, the sockets being closed at their outer ends, as shown at

4. The sockets may be carried by legs 5 provided with laterally extended feet 6 having openings 7, adapted to receive securing elements 8 whereby the feet are attached to 60 the shelf 2, the feet 6 and the sockets 3 projecting in opposite directions, so that, for a purpose to be alluded to hereinafter, the sockets may be disposed directly in front of the stiles 1. The ends of a rod 9 are mounted 65 in the sockets 3, the rod being provided upon its rear side with a longitudinal groove 10. The sockets 3 are supplied with internal longitudinal ribs 11 received in the groove 10, the construction being such that the rod 70 cannot rotate in the sockets.

The invention comprises a plurality of place-markers or book-supports 12, each including a plate 14. Upon one edge of the plate 14 there is a rearwardly extended arm 75 15, and upon the opposite edge of the plate there is a rearwardly extended arm 16, the arms 15 and 16 being spaced longitudinally of the plate 12, for a purpose which will be made manifest hereinafter. The lower end 80 of the plate 14 is flexed rearwardly and upwardly to form a resilient tongue 17 constituting a part of a socket 18. The socket 18 surrounds the rod 9, and forms a pivotal mounting for the plate 14, so that the plate 85 may be swung on the rod in a vertical plane. In order to hold the plate 14 in an up-standing position, a transverse rib 19 is fashioned in the tongue 17, the rib being seated removably in the groove 10 of the 90 rod 9.

The plates 14 are of different widths, depending upon the thickness of the book 24 wherewith any plate is used. The titles on the books are shown at 25 and are duplicated, as indicated at 23, on labels or cards 21 which carry, also, suitable cataloguing indicia shown at 22. The labels 21 may be attached to the plates 14 in any suitable way. In the present instance, tongues 20 100 are struck from the plates 14, the labels being slidably received beneath the tongues.

In practical operation, when a book 24 is on the shelf 2, the book is received between the arms 15 and 16 of the plate 14, 105 the plate standing in an upright position, and being held by the engagement between the rib 19 and the groove 10 in the rod 9. No cataloguing labels are placed upon the books, the labels, shown at 21 being mounted 110 on the plates 14. Owing to this feature, the books are not disfigured, it being neces-

sary, merely, to place the catalogue number on the inner surface of the cover of the book, or elsewhere. When it is desired to remove a book, the plate 14 is swung forwardly into horizontal position, the eye 18 rotating on the rod 9, and the rib 19 automatically disengaging itself from the groove 10 in the rod. The eye 18 is resilient and grips the rod 9 with sufficient force so that the plate 14 will stand at any angle to which it may have been turned. After the book has been removed from the shelf, the plate 14 may be turned up into a vertical position so as to indicate the place to which the book is to be returned. The plates 14 are relatively short, as compared with the height of the books, the titles 25 of the books remaining unobscured, so that it is possible to compare the title 25 on the book with the title 23 on the label 21 at any time. When it is desired to take stock, this can be done readily and rapidly, a glance at any place-marker 12 serving to show whether or not the book is on the shelf.

The place-markers 12 may be slid longitudinally of the rod 9, and because the sockets 3 are located directly in front of the stiles 1, no space is lost at either end of the shelf, 30 it being possible to dispose the terminal members 12 in direct contact with stiles 1, as shown at the left end of Fig. 1. The arms 5 space the sockets 3, and consequently the rod 9, from the forward edge 35 of the shelf 2, so that the tongues 17 may be received between the rod 9 and the forward edge of the shelf 2. Since the tongues 17 extend upwardly and rearwardly, there are no objectionable projections on the plates 40 14 at the lower ends thereof. There is an advantage in spacing the arms 15 and 16 longitudinally of the plate 14 since, when the members 12 are in upright positions, the arm 15 on one member 12 will be disposed 45 directly above the arm 16 on the next member 12. Consequently, two adjoining members 12 will be spaced apart by a distance equal to the thickness of a single arm 15 or 16, and not by a distance equal to the combined thicknesses of the arms. The members 12 may be detached from the rod 9 by springing the sockets 18 off the rod, the re-

siliency of the sockets permitting such an operation.

The shelf 2 may be adjustable, and there is, therefore, a distinct advantage in mounting the sockets 3 on the shelf 2 rather than upon the stiles 1, since, with the construction shown, when the shelf is adjusted, the rod 9 and parts associated therewith are carried along with the shelf.

What is claimed is:

1. The combination with a book-shelf, of a rod extended along the edge thereof, and a combined place-marker and book-support including a resilient tongue extended around the rod to form an eye whereby the marker is mounted on the rod for swinging movement, the tongue and the rod having releasably interengaged rib and groove elements coacting to hold the marker against swinging movement on the rod.

2. The combination with a book-shelf, of a rod extended along the edge thereof, and combined place-markers and book-supports mounted on the rod for swinging movement, the markers having rearwardly extended arms upon their longitudinal edges, the arms upon each marker being disposed at different distances from the rod, whereby an arm on one marker may be disposed directly below an arm on an adjoining marker, thereby to separate the markers by a distance represented by the thickness of one arm.

3. The combination with a book case comprising a shelf, of a rod extended along the edge of the shelf; a combined place-marker and book-support mounted to swing on the rod, the marker and the rod having releasably interengaged parts coacting to hold the marker against swinging movement; and means carried by the book case for supporting the rod, said means including an element engaged with said part of the rod to hold the rod against rotation.

In testimony that I claim the foregoing as my own, I have hereto affixed my signature in the presence of two witnesses.

HENRY BEACH CARRÉ.
